APPARATUS FOR SPLICING STRIPS OF PAPER

William Townley, Fort Dodge, Iowa, assignor to
 United States Gypsum Company, Chicago, Ill.,
 a corporation of Illinois

Application June 25, 1931, Serial No. 546,718

18 Claims. (Cl. 164—99)

This invention relates to an apparatus for splicing paper or other sheet material and has reference more particularly to an apparatus for splicing continuous moving sheets of paper such as are commonly used in the making of plasterboard and for other uses.

In the making of plasterboard, it is common to unwind two strips of paper from two large rolls of paper and deposit plastic material between the two sheets of paper, this plastic material usually consisting of a base of calcined gypsum or other cementitious material. When the roll of paper is exhausted, it has heretofore been necessary to stop the machines long enough to substitute a new roll of paper and start the new strip of paper through the machines.

An object of this invention, therefore, is to provide an apparatus for splicing two strips of paper or other sheet material together while they move continuously so as to avoid stopping the machine and thus slowing up production; also to improve sheet splicing apparatus in other respects hereinafter specified and claimed.

Reference is to be had to the accompanying drawings forming a part of this specification, in which

Fig. 1 is an end elevation of the improved splicing machine.

Fig. 2 is a plan view of the splicing machine.

Fig. 3 is a fragmentary plan view of two strips of paper spliced together with my improved apparatus.

Fig. 4 is a sectional view on a large scale through the spliced paper strip, taken on line 4—4 of Fig. 3.

Fig. 5 is a side elevation of the splicing machine.

Fig. 6 is a sectional elevation through the splicing machine taken on line 6—6 of Fig. 1.

Fig. 7 is a sectional elevation through the splicing machine taken on line 7—7 of Fig. 5.

Fig. 8 is a sectional elevation through the splicing rolls shown in Fig. 7 but with the clutch devices in a different position, and

Fig. 9 is a view similar to Fig. 8 but showing the clutch devices in a still further position.

As seen in Figs. 3 and 4, my improved splicing method consists in causing the free ends of sheets 10 and 11 to overlap a considerable distance, and then by means of rotary cutters, punch semi-circular slits 12 through both sheets where they overlap so as to form tongues 13 in sheet 10 and tongues 14 in sheet 11. Both tongues 13 and 14 will lie in the plane below the planes of sheets 10 and 11 after the punching operation and upon

applying tension to sheet 11, tongues 13 will be moved so as to catch under the slit edge in the lower sheet 11 thus securely interlocking the two sheets 10 and 11 and accomplishing a very strong splice.

This splicing method can be applied to moving sheets of any kind of material, such as paper, where it is desired to splice a sheet from a fresh roll onto the free end of a sheet which has been completely unrolled. As one specific example of its use, it may be applied to the paper cover sheets used in the manufacture of gypsum boards in a manner well known to the art. In the manufacture of such board, two cover sheets are used, an upper cover sheet and a lower cover sheet, a plastic gypsum base being deposited between the two cover sheets and rolled flat so as to make a smooth board of uniform thickness. My improved splicing method will, of course, be applicable to both cover sheets but for the purpose of the present invention, the apparatus for carrying out the method is shown applied only to one cover sheet.

The apparatus consists essentially of a punch roll 16 and a die roll 17, the former carrying a plurality of semi-circular or other shaped punches 18, arranged around a portion of the periphery of said roll, and the roll 17 being provided with a plurality of die recesses 19 adapted to exactly coincide and register with the punches 18 of roll 16. The roll 17 is rigidly secured to a shaft 20 which is rotatably mounted in bearings 21 supported in vertical frame members or standards 22. The roll 16 is mounted upon a tubular shaft 23 which is provided with longitudinal slots 24 for a purpose to be described hereinafter and is rotatably mounted in suitable bearings 25, the latter being supported by the frame members 22. A gear 27 secured to the outer end of shaft 23, meshes with a similar gear 28 secured to the outer end of shaft 20 so that when the shaft 20 is rotated by means of a manually operated crank 30, both rolls 16 and 17 will rotate in unison with the punches 18 registering with the dies 19.

Both rolls 16 and 17 are preferably of a generally cylindrical shape with partially closed ends forming hubs 31 for engagement with the respective shafts. However, both rolls are preferably somewhat eccentric and arranged with thin walls 32 over approximately one-half their circumference so that the rolls are spaced apart a substantial distance when not in operating position thus causing said rolls to be out of frictional contact with the moving strip of paper. The

lower roll 17 may be conveniently arranged in one long cylinder spanning the distance between the upright frame members 22. In some gypsum board machines, it is customary to make three lines of rather narrow board at one time, the lines of board extending parallel and being conveyed by a supporting endless belt. However, when one wide board is made, the upper roll 16 may also be one long cylinder substantially the same length as the roll 17.

When three lines of board are to be formed simultaneously, the upper roll 16 is preferably divided into a plurality, such as three sections 16a, 16b and 16c. Since any one of the three rolls of paper supplying the three lines of gypsum board may become exhausted at different times, it is necessary to provide clutch means for rotating each of the three sections of roll 16 independently of the other two. For this purpose I provide a rod 34 which extends concentrically through the tubular shaft 23, being loosely arranged within said shaft for free axial or sliding movement. In order to cause the controlled axial movement of the rod 34, I provide one end of said rod with a collar 36 secured thereto and provided with a pin 31 registering with a slot 38 formed in a yoke 39 on a lever 40. The lever 40 is pivotally supported at its lower end on a pivot pin 41 which is secured to an outstanding bracket 42 mounted upon one of the standards 22. The upper end of lever 40 is connected by a pivot pin 43 to a bar 44 extending transversely of the machine and being slidably supported at its free end in a slotted bracket 45 secured to one of the frame members 22. A handle 46 is also provided on the free end of the bar 44 so that said bar can be manually actuated by the operator. Suitable slots 47 are formed in the lower edge of the bar 44 so that said slots 40 may engage the bracket 45 and secure the lever 40 in a plurality of adjusted positions.

In order to cause the rotation of any one of the roll sections 16a, 16b, 16c independently of the other two, I provide a pair of clutch plates 49 and 50 secured to the rod 34, suitable slots being formed in said rod to receive said clutch plates and a rivet 51 passing through said rod and each of said clutch plates so as to secure the latter in position. The clutch plates 50 are preferably in the form of a flat H with a central section 52 of reduced width slightly smaller than the diameter of central hubs 53 formed on the inner end of rolls 16a and 16b and on both ends of the roll 16c. A pair of diametrically opposite, radially extending slots 54 are formed in each of the hubs 53 to receive the clutch sections 55 formed on each end of each plate 50 by the slots 52 and extending radially through slots 24 in shaft 23. In Fig. 7, the position of the plates 49 and 50 is such that all three rolls 16 will be caused to rotate simultaneously as would be the case when a wide board is manufactured. The dot and dash position of the plates 49 and 50 as shown in Fig. 7 is such that roll 16c will be caused to rotate but rolls 16a and 16b will remain stationary. In Fig. 8, the plates 50 are so positioned by the manual axial movement of the rod 44 that roll 16a will be caused to rotate and the other two rolls will remain stationary. In Fig. 9, 70 the position of the plate 50 is such that roll 16b will be caused to rotate while rolls 16a and 16c will remain stationary. It is thus seen that four possible combinations of the clutch devices are provided to meet any desired operating condition.

In order to hold any desired number of the sec-

tions of roll 16 stationary while other rolls rotate, three cam locks 57, 58 and 59 are secured upon shafts 60 which are rotatably and adjustably mounted on fixed transversely extending supporting bars 61. Each of the cams 57, 58 and 59 is arranged in one position to engage the punches 18 and prevent the rotation of its respective roll. The cam 59 has a hand lever 63 secured thereto within convenient reach of the operator who can actuate the cam 59 at any desired time. The cam 58 has an operating lever 64 secured thereto and the cam 57 has an operating lever 65. A bar 66 is pivotally connected at one end to the lever 64 and is slidably mounted at the other end in a bracket 67, being provided on its free end with a handle 68 to be manually actuated by the operator. A bar 69 extends transversely of the machine and is pivotally connected at one end to the upper end of the lever 65, being slidably mounted at its other end in the bracket 67. The free end of the bar 69 is provided with a handle 70 in convenient reach of the operator. It is thus seen that all of the control handles for operating the machine are all arranged within easy reach of the operator so that he can quickly make a splice 25 at the proper time without shutting down the board machine.

In order to hold the piece of paper in position just before the splice is to be made, an arcuate shaped table 72 is mounted upon a cross-bar 73 which is secured at its ends to the vertical standard or frame member 22. The lower strip of paper 11 always travels in contact with this table 72, being pressed downwardly upon said table by a pressure plate 74 which is secured to a cross-bar 75, the latter being pivotally secured at its ends in the frame members 22. An operating handle 76 is secured to the bar 75 and is connected by spring 77 to one of the side members 22 so that pressure of the plate 74 on the strip of paper is always maintained. When the operator is about to insert the end of the fresh strip of paper 10 into the splicing machine to accomplish the splice, he pushes down upon the handle 76 to relieve the pressure of the plate 74 on the lower strip of paper 11.

In operation the strip of paper 11 continually passes between rolls 16 and 17, but out of frictional contact therewith, said strip being in frictional contact with the table 72 and being pressed downwardly by means of pressure plate 74 actuated by spring 77.

Where a plurality of strips 11 is being used simultaneously, and a roll from which one of these strips 11 is being supplied is about to become exhausted, the operator adjusts handles 63, 68, and 70 so that only the necessary section 16a, 16b or 16c will be permitted to rotate and the remaining sections are held stationary by the action of the proper cam locks 59, 58, or 57. The operator then actuates handle 46 to adjust the clutch plates 49 and 50 to a position such that the desired roll section will be rotated upon actuation of crank 30. Thereupon, when it becomes nearly time to splice, the operator presses down upon handle 76 to release the pressure of plate 74 on strip 11, and inserts the end of a strip 10 leading from a new roll of material under pressure plate 74, feeding out sufficiently to bring the end of the strip under roll 16, and releases handle 76 so that plate 74 will press strip 10 against strip 11. Just before the free end of the exhausted strip of paper 11 passes over the table 72, the operator turns crank 30 and the punches 18 engage the die recesses 19 so as to form the plurality of 75

semi-circular slits 12 and tongues 13 and 14 which are pressed downwardly out of the plane of sheets 10 and 11 so that by reason of the tension on the sheets said tongues 13 and 14 are caused to go into the position shown in Fig. 4 to firmly lock and splice the two pieces of paper together. Further tension on the strip 11 acts to increase the locking action of the tongues 13 and the splice is accomplished. One rotation of the crank 30 is sufficient to accomplish the splice.

I would state in conclusion that while the illustrated example constitutes a practical embodiment of my invention, I do not wish to limit myself precisely to these details, since manifestly, the same may be considerably varied without departing from the spirit of the invention as defined in the appended claims.

Having thus described my invention, I claim as new and desire to secure by Letters Patent:—

1. In an apparatus for splicing moving strips of paper, a plurality of punches mounted for independent rotation and arranged adjacent one side of a moving strip of paper, and a rotatably mounted die member positioned adjacent the opposite side of said strip of paper, said die member registering and rotating in unison with said punches to form slits and tongues in said strip and a second superposed strip, for splicing said strips together.

2. In an apparatus for splicing moving strips of material, a plurality of groups of rotatably mounted punches arranged adjacent one side of a moving strip of material, a rotatably mounted die member positioned adjacent the opposite side of said strip of material, means for rotating one or more groups of said punches in unison with said die member so as to cause said punches to register with said die member and form slits and tongues in said strip and a second superposed strip, for splicing said strips together.

3. In an apparatus for splicing moving strips of material, a roll comprising a plurality of co-axially mounted roll sections arranged adjacent one side of a moving strip of material, a second roll rotatably mounted adjacent the opposite side of said strip, means for rotating one or more of the roll sections in unison with the second roll, and co-operating punches and die means associated with said rolls and arranged to register upon rotation so as to form slits and tongues in said strip and a second superposed strip, for splicing said strips together.

4. In an apparatus for splicing moving strips of material, a roll comprising a plurality of co-axially and rotatably mounted roll sections arranged adjacent one side of a moving strip of material, means for selectively rotating one of said sections so as to form an operative splicing roll, a second roll positioned adjacent the opposite side of said strip of material, means for rotating said operative roll section and said second roll in unison, punches and die means associated with said rolls and adapted to register upon rotation so as to form slits and tongues in said strip and a second superposed strip, for splicing said strips together.

5. In an apparatus for splicing moving strips of material, a roll comprising a plurality of co-axially and rotatably mounted roll sections, clutch members for independently engaging said roll sections, means associated with said clutch members for causing the rotation of one or more of said sections while the remaining sections remain stationary, a second roll arranged adjacent the opposite side of said strip of material,

and punch and die means associated with said rolls and arranged to rotate with said rolls and register so as to form slits and tongues in said strips and second superposed strip, for splicing said strips together.

6. In an apparatus for splicing moving strips of material, a plurality of co-axially and rotatably mounted rolls, clutch members associated with said rolls, adjusting means for causing said clutch members to selectively engage one or more of said rolls, driving means associated with said clutch members for causing the rotation of an operative selected roll, means for holding the remaining rolls stationary, another roll arranged adjacent the opposite side of said strip of material, and punch and die means associated with said rolls and arranged to register upon rotation so as to form interlocking tongues in said strips and a second superposed strip, for splicing said strips together.

7. In apparatus of the character described, adjacent normally inoperative roll members, co-operating punch and die elements on said rolls adapted to operate upon sheet material passing between said rolls when they are rotated, means for simultaneously and intermittently rotating said rolls, said rolls being arranged to be substantially out of contact with each other while inoperative whereby to permit said sheet material to pass freely therebetween until said rolls are rotated, and manual means providing optional control for engagement and clearance of said punch and die elements.

8. In apparatus of the character described, normally stationary punch and die rolls in co-operative relationship and arranged for the passage therebetween of sheet material to be operated on, and means for intermittently rotating said rolls, said rolls being arranged to operate on said sheet material only when the same are rotated, and manual means providing optional control for engagement and clearance of said punch and die rolls.

9. In apparatus of the character described, adjacent eccentric punch and die rolls in cooperative relationship and arranged for selective intermittent rotation, and means for rotating said rolls, said rolls being arranged to permit free passage of sheet material to be operated upon therebetween until rotation of said rolls.

10. In apparatus of the character described, adjacent punch and die rolls, means for simultaneously and intermittently rotating said rolls, one of said rolls being provided with punch elements over a portion of its periphery, and the other roll being provided with complementary die elements, said rolls being arranged to normally remain stationary and with the punch and die elements out of register, said punch and die elements being brought manually and optionally into operative register only when said rolls are rotated.

11. In apparatus of the character described, adjacent eccentric rolls, means for simultaneously rotating said rolls, said rolls being arranged to come into close proximity only with the projecting portions of their periphery, and cooperating cutting elements on said projecting portions and adapted to operate upon a strip of sheet material passing between said rolls.

12. In apparatus of the character described, an eccentric roll provided over the projecting portion of its periphery with outstanding punch means adapted to cut individual tongues in sheet material.

13. In apparatus of the character described, an

eccentric roll provided over the projecting portion of its periphery with recessed die means adapted to cooperate with punch means for cutting individual tongues in sheet material.

5 14. In apparatus of the character described, a roll comprising a plurality of sections, drive means, means in association with said drive means for selectively engaging any one or more of said roll sections to rotate the same, and means for holding stationary any roll section not rotatably engaged.

15 15. In apparatus for splicing sheet material, means for cutting interlocking tongues in moving sheet material and adapted to operate on a sheet 15 which is the whole width of the apparatus or on one of a plurality of separate parallel strips, said means being in a plurality of sections disposed transversely of the moving material, and means for actuating any one of said sections while the 20 remaining sections remain inoperative.

16 16. In apparatus of the class described, a hollow shaft, a plurality of independently rotatable roll sections mounted on said shaft, a rod within said shaft, and clutch plates on said rod and extending through slots in said shaft, means on said roll sections for engagement with said clutch 25

plates, and means for moving said rod to vary the position of said clutch plates to engage and cause rotation of any one of said sections when said shaft is rotated.

17. In apparatus of the class described, a shaft, 5 a plurality of independently rotatable roll sections mounted on said shaft, clutch means associated with said shaft, means on said roll sections for engagement with said clutch means, said clutch means being adapted to selectively engage and cause rotation of any one of said sections when said shaft is rotated, and means for retaining stationary any roll not engaged for rotation.

18. Apparatus for splicing moving sheet material, comprising means for cutting interlocking tongues in said material, and means for manually and optionally causing operation of said cutting means when a splice is to be made, said cutting means being arranged during inoperative intervals to permit free movement of said sheet material adjacent thereto and being adapted to operate on said material during uninterrupted movement of said material when said cutting means is actuated.

20 WILLIAM TOWNLEY.
